UNITED STATES PATENT OFFICE.

LEONARD C. PETERS, OF PROVIDENCE, RHODE ISLAND.

MEANS FOR REDUCING THE CAPACITY OF FIRE BOXES.

Application filed December 22, 1921. Serial No. 524,066.

To all whom it may concern:

Be it known that I, LEONARD C. PETERS, a citizen of the United States, residing at Providence, in the county of Providence and State of Rhode Island, have invented new and useful Improvements in Means for Reducing the Capacity of Fire Boxes, of which the following is a specification.

The object of my invention is the provision of simple, easily applied and efficient means for reducing the capacity of a stove fire box as when it is desired to build a small fire in the box.

To the attainment of the foregoing, the invention consists in the improvement as hereinafter described and definitely claimed.

In the accompanying drawings, forming part of this specification:—

Figure 1 is a plan view, partly broken away, showing my improvement as properly positioned in the fire box of a stove.

Figures 2 and 3 are vertical sections taken in the planes indicated by the lines 2—2 and 3—3, respectively, of Figure 1.

Figures 4 and 5 are detail perspectives of the sections that constitute the partition wall of my improvement.

Figure 6 is a detail perspective of the brace for maintaining the said partition wall in working position.

Similar numerals of reference designate corresponding parts in all of the views of the drawings.

The fire box 1 is provided with a refractory lining 2 and with a grate 3 and is otherwise of the ordinary construction or of any other appropriate construction for the use of my improvement.

My improvement comprises a mat 4 of asbestos or other appropriate imperforate fire-proof material, a partition wall 5, and a brace 6 for maintaining the partition wall 5 in working position.

As best shown in Figure 4 the partition wall 5 comprises two sections 7 and 8, each of the sections being rabbeted as indicated by 9 and each being provided in its reduced portion with an oblong slot 10, said slots 10 being designed to be registered when the reduced portions of the partition sections are lapped as shown in Figures 1, 2 and 3. It will also be noticed that each of the partition sections 7 and 8 is provided with a depending projection 11, the said projections 11 being designed and adapted to enter an opening of the grate 3, Figures 2 and 3,

so as to assist materially in maintaining the partition in working position in the fire box.

The brace 6 is preferably of the configuration shown, and is designed to bear at its outer end against one end wall of the fire box. The said brace 6 rests solidly on the mat 4 and bears at its inner end 12 against the partition 5. It will also be noticed that the brace 6 is provided near its inner and outer corner with a stem 13 on which is a vertically-disposed T-head 14.

In assembling the partition 5 and the brace 6 precedent to putting the same in a fire box, the brace 6 is held in horizontal position, and the T-head 14 is passed forwardly through the registered openings 10 in the sections 7 and 8, after which the brace 6 is turned to upright position with the result that the T-head 14 will rest in upright position at the opposite side of the partition 5, with reference to the major portion of the brace so that the partition and the brace will be securely interlocked, and the sections 7 and 8 of the partition will be strongly secured in their proper relative position.

In putting my improvement into use, the mat is laid on the part of the grate that it is desired to put out of commission, after which the connected partition 5 and brace 6 are placed in the fire box, with the brace 6 on the mat 4 as illustrated.

By particular reference to Figure 2 it will be observed that when my improvement as described in a fire box about one-half of the fire box is rendered idle so that a small fire may be maintained in the fire box at the left of the partition 5 in Figure 2 without liability of any draft being wasted by passage through the idle portion of the fire box.

When it is desired to utilize the full capacity of the fire box 1 it will be manifest that my improvement may be expeditiously and easily removed from the fire box, and when it is desired to store the improvement, the brace 6 may be quickly and easily disconnected from the partition sections 7 and 8, and the said partition sections may be readily disconnected from each other so that the whole improvement can be packed in a space of small compass.

I have entered into a detailed description of the construction and relatively arrangement of parts embraced in the present and

preferred embodiment of my invention in order to impart a full, clear and exact understanding of the said embodiment. I do not desire, however, to be understood as 5 confining myself to the said specific construction and relative arrangement of parts inasmuch as in the future practice of the invention various changes and modifications may be made such as fall within the scope 10 of my invention as defined in my appended claim.

Having described my invention, what I claim and desire to secure by Letters-Patent, is:—

15 Means to reduce the capacity of fire

box, comprising an imperforate fireproof mat, a brace adapted to be superimposed on said mat, a partition including sections with lapped portions, and horizontal oblong openings therein, and a stem projection from 20 the end of the brace and terminating in an upright T-head, said stem adapted to extend through said openings in the partition sections, and said T-head adapted to rest at the opposite side of the partition with 25 reference to the major portion of the brace.

In testimony whereof, I affix my signature.

LEONARD C. PETERS.
